SHEET FEEDING APPARATUS

Lloyd G. Murray, Youngstown, Ohio, assignor to The Aetna-Standard Engineering Company, Pittsburgh, Pa., a corporation of Ohio

Application April 20, 1955, Serial No. 502,615

9 Claims. (Cl. 271—11)

This invention relates to the handling of steel sheets or the like and more particularly to an improved apparatus for removing such sheets from one or more stacks or piles and feeding them to other processing apparatus, such as a tinning machine or pickling tanks.

After sheet steel material leaves the forming rolls it is usually cut into individual units of the desired length and these units or sheets are arranged in stacks or piles. Further processing operations, such as tinning, are commonly performed on such sheets and problems are encountered in feeding them in the proper and most efficient manner from the stacks to the tinning machine or other apparatus. As the sheets must pass through the tinning machine or the like individually and spaced apart, i. e., not overlapped or doubled, it is necessary to provide means for removing them from the stacks one at a time and transmitting them as rapidly as possible to the feed rolls which carry them along to the next processing apparatus.

The width of the stacks of sheets that are to be handled by the feeding apparatus necessarily varies from time to time, depending on what size sheets are being processed, and accordingly it is an object of this invention to provide apparatus whereby either single relatively wide sheets or sets of several relatively narrow sheets may be fed to the next machine from one or several stacks automatically and without change or adjustment of the feed apparatus.

Other objects of my invention include the provision of sheet feeding apparatus of the type referred to whereby single sheets will be removed from each of one or several stacks of sheets and fed to the succeeding processing apparatus with a minimum delay between successive sheets or sets of sheets, and in such a manner that a new cycle of the feeding apparatus will not start until the sheets being fed are completely out of the way; the provision in sheet feeding apparatus of the type described of means whereby the feeding apparatus may not be started unless a suitable current supply is available, and whereby the feeding cycle will automatically repeat promptly after a given sheet or set of sheets has been fed; the provision of sheet feeding apparatus which will automatically adjust for sheets of various lengths so that, regardless of the length of the sheets being fed, the cycle will repeat immediately after the sheet, or set of sheets, being handled has moved out of the path of the feeding apparatus; and the provision of a fully automatic sheet feeding apparatus which is efficient in operation, requires a minimum of maintenance and repair, and will operate continuously over long periods of time without attention or adjustment.

The above and other objects of my invention will appear from the following description of one embodiment thereof, reference being had to the accompanying drawings in which:

Figure 1 is an illustrative side elevational view of my feeding apparatus, the pickup arms and suction heads being shown in fully advanced positions;

2

Figure 2 is a view similar to Figure 1 but illustrating the pickup arms and suction heads in fully retracted position, a sheet being shown in engagement with the magnetic rolls and being advanced toward the succeeding processing apparatus;

Figure 3 is a diagrammatic illustrative elevational view showing several stacks of sheets in feeding position, the upper magnetic roll, the contactor rings on the upper magnetic roll shaft, and the electrical connections leading from the rings to the control mechanism;

Figure 4 is an illustrative wiring diagram showing the electrical controls and the solenoid which operates the valve means for controlling the advancing and retracting movements of the pickup arms, the various elements being shown in their completely "off" or non-operating positions and conditions;

Figure 5 is a view similar to Figure 4 but illustrating the elements of the control mechanism in the positions they assume after the main switch and starting button have both been moved to the "on" position, but while the pickup arms and suction heads are still fully retracted, ready to start their advancing movement;

Figure 6 is a view similar to Figure 4 but illustrating the positions and conditions of the elements after the pickup arms and suction heads have advanced to their final forward position and are just ready to start retracting to remove the top sheet from each stack;

Figure 7 is a view similar to Figure 4 but illustrating the positions and conditions of the elements after the pickup arms and suction heads have retracted to a point just beyond where the suction heads release the sheets but before the arms have reached fully retracted position; and

Figure 8 is a view similar to Figure 4 but illustrating the circuits, etc., when the pickup arms and suction heads are in their fully retracted positions; the sheet or sheets being still engaged and fed by the top magnetic roll while the pickup arms are held in retracted position ready for repetition of the feeding cycle immediately after all the sheets have left the magnetic roll.

As will be seen from Figures 1 and 3, my sheet feeding apparatus is mounted in a frame structure or housing F having spaced end panels 1 and 2 suitably supported on the floor or foundation and maintained in proper relationship to each other as by transverse members 3 (Figure 3). In Figure 1 the upper portion of the end panel 2 has been broken away more clearly to illustrate the structural arrangement of the apparatus.

Extending across between the end panels 1 and 2 is an angularly mounted stack support structure 4 on which one or more stacks or piles P, P' and P'' of sheets are supported in slightly inclined position. Also extending between and supported by the end panels 1 and 2 are the main pickup arm support shaft 5, the shaft 6 for the lower magnetic rolls 7, the shaft 8 for the upper magnetic rolls 9, and the drive shafts for the two sets of takeoff rolls 10—11 and 12—13. The sheet guides or deflectors 14 and 15 are also suitably supported between the end panels 1 and 2.

In Figure 2 a single sheet S has been removed from the stack P and moved into engagement with the magnetic rolls 7 and 9 by the mechanism and in the manner to be later described. As the magnetic rolls, during operation, are continuously driven in the directions indicated the sheet S will be fed upwardly thereby and its upper end will engage the guide or deflector 14 which, in cooperation with the lower deflector or guide 15, will direct the leading edge of the sheet S into the take-off rolls 10—11 which will carry it on to the second set of takeoff rolls 12—13 and thence to the next processing apparatus. In Figure 2 a sheet S', which has been removed from the stack P and advanced by the magnetic

rolls 7 and 9, is shown being moved on to the succeeding processing equipment (for example a galvanizing machine). So also in Figure 1 a sheet S" is shown being advanced by the rolls 10-11 and 12-13.

Mounted on and keyed to the pickup arm support shaft 5 are three sets or pairs of pickup arms which are diagrammatically indicated on Figure 3 at 16-17, 18-19, and 20-21. As these arms, and the suction heads carried by each of them, are substantially identical in structure and function, only the arm 16 which is adjacent the end panel 2 and is shown in detail in Figures 1 and 2, need be specifically described. Shaft 5 is journaled in the end panels 1 and 2 and, in addition to being aligned and keyed to shaft 5, the series of pickup arms 16-17, 18-19, and 20-21 are also interconnected by a tie rod or operating bar 22 (see Figure 3). Secured to the upper end of pickup arm 16 (and of each of the other pickup arms) is a bracket member 23 in which the tubular stem 24 of the suction head, generally indicated at H, has a sliding fit. At the forward end of the stem 24 is a rubber or the like suction cup or grip member 25 of well known type having a resilient lip portion 25' which is adapted to engage the face of the sheets S in the stack P and, when suction is applied as will be described later, to firmly hold the sheet. Interposed between the bracket member 23 and the inner end of suction grip member 25 is a spring 26 which, as seen in Figure 1, is in compressed condition and, as seen in Figure 2, is in extended position. The function and operation of this spring will appear later.

In order to retract the pickup arms from full advanced position as seen in Figure 1 to full retracted position as seen in Figure 2, and to advance same from retracted to advanced position, fluid pressure cylinder means are provided. In the illustrated embodiment the cylinder 27 contains a piston 28 mounted on one end of piston rod 29. The opposite end of piston rod 29 is pivotally secured by a connecting member 30 to the operating bar 22 which connects the entire series of pickup arms. Thus all of the arms are operated simultaneously from a single power source. In order to accommodate the angular swinging movement of the pickup arms 16, etc., the cylinder 27 is pivotally supported at 31 on suitable brackets 32 carried by a platform structure 33 mounted between the end panels 1 and 2.

To control the movement of the piston 28 in the cylinder 27, and thus control the oscillating movement of pickup arms 16, etc., I provide a four-way valve which is diagrammatically illustrated at V in Figures 1 and 2. A source of supply of fluid under pressure is available in supply pipe 34 which has a shut-off valve 34' therein. As illustrated in Figure 1 the valve V is so positioned that fluid under pressure from supply pipe 34 will pass through pipe 35, the passage in the valve body portion 36, and pipe 37 to the right hand end of cylinder 27. At the same time left hand end of cylinder 27 is connected to atmosphere through pipe 38, the valve body 36, and valve outlet 39.

It will be observed that when valve V is in the position of Figure 1 the piston 28 will be moved to the left hand end of cylinder 27 and the pickup arms 16, etc., together with suction heads H, will be moved to their fully advanced positions as seen in Figure 1. This movement of piston 28 takes place freely because the fluid in the left hand end of cylinder 27 may, as previously noted, be discharged to atmosphere while fluid under pressure is being applied to the right hand end of cylinder 27.

As diagrammatically illustrated in Figures 1 and 2, the valve V includes an operating arm member 40 connected to the plunger 41 of a solenoid M which is pivotally mounted on a bracket 42. As will appear more fully later, the solenoid M is of the type which, when electrically energized, moves the plunger 41 to the left (Figures 1 and 2) and when de-energized permits the spring 43, which surrounds the end of plunger 41 and 75

extends between the housing of the solenoid M and an enlarged head 41' on plunger 41, to move the plunger 41 to the right. Thus Figure 1 illustrates the solenoid energized, pickup-arm advancing position of the solenoid M and valve V, while Figure 2 shows the solenoid de-energized, pickup arm retracting position of these elements.

In order to produce suction at the resilient lip portions 25' of the grip portions 25 of suction heads H during the proper portions of the operating cycle, the tubular stem portions 24 of each suction head H (it being understood that there is a suction head H on each of the pickup arms 16-21, inclusive) are connected by flexible hose sections 44 to a transverse pipe or header 45, one end 46 of which 10 extends through an arcuate slot 47 in end panel 2. A section of flexible hose 48 (part of which is shown in phantom lines in Figures 1 and 2 to facilitate illustration of other parts) extends from the end portion 46 of header pipe 45 and connects to the vacuum line 49 through a short rigid pipe section 50.

Mounted on the outer face of end panel 2 is the vacuum or suction producing cylinder 51 to the left hand end of which the vacuum line 49 is connected. A piston 52 in cylinder 51 is secured to the end of piston rod 53 which 15 projects out through the right hand end of cylinder 51 and has a yoke member 54 at its opposite end. An operating arm 55 is mounted on and keyed to the end portion of pickup arm shaft 5 which projects outwardly beyond the end panel 2. The upper end of arm 55 is 20 slotted at 56 and a pin 57 is carried by yoke 54 and extends through slot 56. This arrangement accommodates the angular movement of arm 55 and provides an operating connection between the upper end of arm 55 and the piston rod 53.

Mounted at the end of an extension portion 58 of vacuum line 49 is a vacuum relief valve 59. The function of this valve will be described later but it may be pointed out here that the valve is normally held closed by suitable means, such as a spring, and is provided with an outlet 60 adapted, when the valve is opened, to establish atmospheric connection through the valve to the vacuum piping system. To open the valve 59 it is necessary to depress the operating pin or plunger 61 which is normally held in its outer, valve closed, position by the 25 valve spring. The operating arm 55 includes a downwardly extending portion 55' which carries an adjustable valve contactor finger 62 at its lower end.

Before describing the control mechanism of my apparatus the operation of the above described elements in picking a sheet off of one of the stacks of sheets and transferring same into engagement with the magnetic rolls 7 and 8 will be explained. In the following description reference will be made only to the single pickup arm 16 and its vacuum head H, and to a single sheet S which is being handled, but it will be understood that all of the pickup arms and vacuum heads operate simultaneously and that, if three stacks of sheets are disposed as seen in Figure 3, three sheets will be picked up at a time. In like manner if only two stacks are positioned on the sheet support, or if a single stack of wide sheets is being handled, the several pickup arms and vacuum heads will function automatically to feed the sheets which are in position to be picked up.

In Figure 1 pickup arm 16 is in its fully advanced position. The resilient lip 25' of the suction head H has engaged the face of the generally vertically disposed outer sheet S above the horizontal center line thereof, and the bracket or collar portion 23 at the upper end of arm 16 has been slid forward on the tubular stem 24 of head H to compress the spring 26 and effect firm seating of the lip portion 25' on the sheet. When the arm 16 is in this full advanced position the piston 52 is disposed close to the left-hand end of the vacuum cylinder 51 from which extends the vacuum line 49.

As the arm 16 starts its generally horizontal retracting

movement the collar 23, at first, merely slides on the tubular stem 24 and the spring 26 holds the lip 25' of the vacuum head H firmly against the sheet S. During this initial movement of the arm 16 the piston 52 will be moved to the right in the cylinder 51. This movement will, because the pipe connections are air-tight and because the valve 59 is closed, produce a reduced pressure in the piping connections 49, 50, 48, 46, 45, 44 and 24 which lead to the suction grip member 25. Thus, by the time the end face of collar 23 engages the adjustable stop nuts 24' on the tubular stem 24 sufficient vacuum will have been produced within the suction grip member 25 to firmly adhere the sheet S thereto. Now, as the arm 16 continues its retracting movement it, together with one or more of the other pickup arms and suction heads, will pick the single sheet S off of the stack P and move it bodily into engagement with the magnetic rolls 7 and 9. During this transfer movement the sheet S is, in effect, hung or suspended from the suction heads and is generally vertically disposed.

At the time the sheet S reaches a plane extending tangent to both of the vertically spaced magnetic rolls and engages these rolls, or very shortly thereafter, the valve 59 is opened by engagement of the contactor finger 62 with the operating stem or plunger 61 of the valve. The exact timing of the opening of the valve 59 may be regulated by suitable adjustment of the position of the finger 62 at the end of the extension 55' of the operating arm 55, it being seen in the drawings that finger 52 is provided with a screw and slot connection to permit such adjustment.

As soon as valve 55 is opened, the vacuum system is vented to atmosphere and the suction at the head H is broken. This, of course, causes the lip portion 25' to be released from its grip on the sheet S and the pickup arm 16 then continues to move in retracting direction until it reaches the fully retracted position shown in Figure 2. The fully retracted and fully advanced positions of the arm 16 may be established and controlled by any suitable stop means which may be within the cylinder 23 or at any other suitable location.

During the advancing movement of the arm 16 from the position shown in Figure 2 to that shown in Figure 1, the piston 52 is moved to the left in the vacuum cylinder 51. As the valve 59 is closed at this time this will cause air to be discharged out through the open lip portion 25' of the suction head H. When the lip 25 engages the sheet S on the outer face of the stack P its advancing movement is of course stopped. However, the arm 16 continues to advance during the time the spring 26 is being compressed. Due to the form and natural characteristics of the lip portion 25' air will be discharged between the lip and the sheet without excessive resistance until the final advance position of the arm 16 is reached as seen in Figure 1. However, during the retracting movement of the arm, as previously explained, reduced pressure is immediately created within the vacuum head H and this reduced pressure is immediately effective to produce the required grip on the sheet. The provision of the spring 26 not only permits the arm 16 to continue to move after the vacuum head H engages the sheet so that there may be an initial movement in the reverse direction to create a vacuum to cause the sheet to be attached to the head H, but also automatically compensates for the varying position of the top sheet of the stack P as sheets are removed one by one therefrom.

For control purposes to be later described, a reverse limit switch 65, diagrammatically indicated on Figures 1 and 2, is supported on the end panel 2 and has an operating member 65' projecting outwardly therefrom and adapted to be engaged by a pin 66 on the arm 55 when said arm reaches its fully retracted position (Figure 2). In like manner a forward limit switch 67 is mounted on end panel 2 and has an operating member 67' which, as seen in Figure 1, is engaged by the pin 66 when the arm 16 reaches its fully advanced position.

Having described the pickup and feeding portions of my apparatus and explained generally their mode of operation, the mechanism for controlling and timing the functions and operations thereof will now be described.

5 The electrical circuits and the various elements of the control apparatus are diagrammatically shown in Figures 4 to 8 inclusive, the several views being similar but illustrating the connections, etc., which are established during several different phases of the operating cycle.

10 Figure 3 illustrates schematically the contactor rings (to be later described) on the upper magnetic roll shaft 8 and the connections thereto.

In Figure 4 the control mechanism is shown in full "off" or non-operating position. The main current supply to 15 the apparatus comes through power lines 70-71 which are connected to a suitable source such as 220 volts A. C. The main switch 72, when open as seen in Figure 4, breaks the main power supply and accordingly the apparatus is completely inoperative. A transformer 73 having a primary 73' and a secondary 73" may be considered

20 as the source of solenoid energizing current. The secondary 73" supplies a reduced voltage (for example 110 volts A. C.) to the lines or conductors 74 and 75 in the operating circuit. These conductors 74 and 75 extend to 25 the primary 76' of a second transformer 76, the secondary 76" of which provides the source of control current and is connected to lines or conductors 77 and 78 in the control circuit.

Connected across the lines 74 and 75 is the energizing 30 coil of a relay 79. This relay 79 has two normally open (i. e., open when the relay is de-energized) contacts 79' and 79". The connection 80, which includes the energizing coil of relay 79 and extends between lines 74 and 75, also includes the starting push button or switch 81, 35 a stop push button or switch 82 and the contacts 83' of a relay 83 the energizing coil of which is connected across between lines 77 and 78 by a conductor 84. It will be understood that although the various relays included in Figures 4-8 are shown with their energizing coil portions spaced from their contact portions there are the usual operating means whereby these contacts are opened or closed when the relays are energized or de-energized.

Another relay 85 has its energizing coil connected across 40 lines 74 and 75 by a conductor 68. Relay 85 has a normally open contact 85' disposed in the conductor 68 which also has, in series arrangement therein, the normally closed forward limit switch 67, the contact 79" of relay 79, and the normally closed contact 86' of relay 86. Connected around the contacts 85' and 86' by a conductor 87 45 are the normally open reverse limit switch 65 and the normally closed contact 86" of relay 86.

As best seen in Figure 3, the upper magnetic roll shaft 5 8 carries three pairs of contactor rings, to-wit: 87-88, 89-90, and 91-92. These contactor rings are of a 55 diameter equal to or just slightly larger than the diameter of the magnetic rolls 9 and are adapted to be engaged by the sheets being handled when these sheets are held against the magnetic rolls. It will be understood that the sheets will effect electrical connection between the adjacent rolls of each pair so long as they are in contact therewith. Brushes 87', 88', 89', 90', 91' and 92' make electrical contact with their respective contactor rings. These brushes are also shown on Figures 4-8 and it will be seen that one brush of each pair, namely brushes 88', 90' and 60 92', are connected by a conductor 93 to the line 77 while the other brush of each pair, namely brushes 87', 89', and 91', are connected to line 78 through conductor 94 in which the energization coil of relay 86 is disposed. Conductor 77 is connected to the machine frame F which 65 in turn is grounded at 100 for purposes which will be later explained. The solenoid M is, of course, in the operating circuit and is connected around the energizing coil of relay 85 by conductors 95 and 96. As has been previously explained this solenoid M actuates the control valve V 70 of the fluid pressure cylinder 27.

As seen in Figure 4 the main switch 72 is open. The starting switch or push button 81 is also open. When this condition obtains current does not flow through the operating circuit (lines 74 and 75, etc.) or through the control circuit (lines 77 and 78, etc.) and the relays 79, 83, 85, and 86 are all de-energized. However, because the pickup arm 16 is in its fully retracted position and the pin 66 on arm 55 is engaging the operating member 65' of the reverse limit switch 65, this limit switch, which is normally held open by suitable spring means, is closed as is indicated in Figure 4. The forward limit switch, and all of the relay contacts are in their normal positions which have been noted above.

In Figure 5 the control mechanism is illustrated in the condition which obtains after the main switch 72 has been closed and after the starting push button 81 has been operated to complete its contacts in the conductor 80. The pickup arm 16 has, however, not yet left its fully retracted position of Figure 2 but is just about to do so.

As soon as the main switch 72 is closed the circuit through the primary 76' of transformer 76 is completed causing a current of reduced voltage (for example 24 volts) from the secondary 76" to be applied to the conductors 77 and 78 and to flow through conductor 84 and the actuating coil of relay 83. Upon relay 83 being thus energized its normally opened contact 83' immediately closes as seen in Figure 5. The start push button 81 and the stop switch 82 also now being closed, the circuit is completed through the energizing coil of relay 79 and the normally open contacts 79' and 79" thereof immediately close, as is also seen in Figure 5. When contact 79' closes it locks in the relay 79 so that this relay continues to be energized even after pressure on the start push button 81 is removed and it returns to its open or "off" position. When the contact 79" in conductor 68 closes the circuit to the energizing coil of relay 85 is completed from conductor 74 through the still closed reverse limit switch 65, the normally closed contact 86" of relay 86, the conductor 87, the closed contact 79", the conductor 68 and the normally closed forward limit switch 67 to conductor 75. As soon as relay 85 is energized its contact 85', which lies in conductor 68, immediately closes thus locking in relay 85 and holding it energized even after the pickup arm 16 moves away from the reverse limit switch 65, thus permitting switch 65 to return to its normally open position. This movement of the pickup arm 16 occurs as soon as contact 79" closes as this, in addition to energizing the relay 85, also completes the circuit to and energizes the solenoid M, causing it immediately to shift the valve V from the position of Figure 2, in which fluid pressure is applied to hold the arm 16 in retracted position, into the position of Figure 1 in which fluid pressure is applied to move piston 28, piston rod 29, and pickup arm 16 in advancing direction. As noted above, as soon as arm 16 moves forward a very slight distance the reverse limit switch 65 will return to its normal or open position but relay 85 stays energized, being locked in by its contact 85', and the solenoid M continues to be energized.

Thus the pickup arms will continue to advance until they reach fully advanced position (Figure 1) at which time the pin 66 on arm 16 engages the operating member 67' of normally closed forward limit switch 67, moving same into open position. When this occurs the condition shown in Figure 6 will be produced.

As the circuit to the solenoid M is broken upon the opening of the forward limit switch 67 the valve V will be moved by the spring 43 from the pickup arm advancing position of Figure 1 into the pickup arm retracting position of Figure 2. It will be understood that in the condition of Figure 6 the start push button 81 will be open as the operator's pressure thereon will have been released. However, relay 79 will still be energized, being locked in by contact 79'. When forward limit switch 67 opens,

relay 85 is de-energized and its contact 85' will return to its normally open position. The normally open reverse limit switch 65 will remain open during retracting movement of the arm 16, relay 83 will remain energized thus holding its contact 83' closed, and, until the sheets engage the contactor rings 87-92, relay 86 will remain de-energized holding its normally closed contacts 86' and 86" in closed position.

As has been previously explained, the suction heads H 10 pick up the top sheet from the stack P because of the suction produced by movement of the piston 52 in the vacuum cylinder 51. As the pickup arms retract the sheet, or sheets, are lifted and carried into contact with the magnetic rolls 7 and 9. Just as the sheets engage 15 these rolls the contactor finger 62 on arm 55' opens the vacuum relief valve 59 thus releasing the suction heads H from the sheets and permitting the pickup arms to continue to retract.

As soon as a sheet is caused to engage the upper magnetic roll 9, and thus to complete the circuit between adjacent pairs of the contactor rings 87-88, 89-90, or 91-92, the condition shown in Figure 7 is produced. As the arm 16, together with the arm 55 and pin 66, thereon have moved away from and out of engagement 25 with the operating member 67' of forward limit switch 67, this switch has returned to its normally closed position. The circuit to the energizing coil of relay 86 has however been completed from conductor 77 through the conductor 93, the brushes 88', 90', 92', contactor rings 88, 89, 30 90, the sheet or sheets, conductor rings 87, 88, 89, brushes 87', 89', 91', and conductor 94 to conductor 78. It will be understood that the circuit to relay 86 will be completed whether there are three sheets, S, S' and S", in engagement with the respective pairs of contactor rings 35 as illustrated in Figure 7 or only a single sheet is being handled and is in engagement only with one pair of contactor rings.

The machine frame F is connected to the conductor 77 and is also grounded at 103, and thus the sheets S, S' and S" are also grounded through engagement with the magnetic rolls 7 and 9. Contactor rings 87, 89 and 91, which are connected to conductor 94 and thence to conductor 78 through relay 86, are electrically connected to the upper magnetic roll shaft 3, which is also grounded through the machine frame. Contactor rings 88, 90 and 92, which are connected to conductor 77 through conductor 93 are insulated from the shaft 3. Thus when a sheet engages one of the magnetic rolls, and one of the contactor rings 87, 89 or 91, the circuit through relay 86 will be completed even though contact is not made or maintained between the sheet and another contactor ring of any of the three pairs.

The condition illustrated in Figure 7 is that which obtains just after a sheet or several sheets have been brought into engagement with the magnetic rolls but before the pickup arms have moved to their fully retracted positions. In Figure 8 the condition is shown after the pickup arm 16 has reached fully retracted position as seen in Figure 2. Normally open reverse limit switch 65 has now been closed by engagement of pin 66 with the operating member 65' of the limit switch. However, as a sheet or sheets are still in contact with the upper magnetic roll 9 and with one or more pairs of the contactor rings 87-92, the relay 86 is still energized and its contacts 86' and 86" are still open. Thus the circuit to relay 85 is held open and the solenoid M remains de-energized. Accordingly, the valve V remains in the position of Figure 2 and the operating fluid pressure in cylinder 27 holds the pickup arms and associated parts in their fully retracted positions as long 60 as the circuit to relay 86 remains closed. This occurs until the trailing edge of the last sheet being handled leaves the upper magnetic roll 9 and breaks all connections, either between a pair of contactor rings or one of the contactor rings 87, 89 or 91 and the ground, to 70 relay 86. When the last sheet so leaves the contactor

rings the relay 86 is immediately de-energized permitting its normally closed contacts 86' and 86'' to reclose. This action will return the mechanism and the circuits to the condition shown in Figure 5 (except that push button 81 will be open) in which the solenoid M is energized to shift the valve V into arm advancing position and is locked in by contact 83' of relay 85. The cycle above described then automatically repeats itself.

It will be observed that unless there is a suitable supply of low voltage current between the conductors 77 and 78 it will be impossible to start the feeding apparatus even though the main switch 72 and starting button 81 are both closed. This safety feature results from the fact that unless the relay 83 is energized by current in the circuit 77-78 its contacts 83' will be open and it will be impossible to energize relay 79 and start the cycle of operation even though the push button start switch 81 is actuated. By providing the contactor ring arrangement advancing movement of the pickup arms from their fully retracted positions is positively prevented until after the last sheet being handled has moved upwardly away from the top magnetic roll and thus out of the path of the vacuum heads, etc. My control mechanism not only prevents the pickup arms from advancing while a sheet is in the way but also insures that the pickup arms do advance immediately after the path is cleared so that there is a minimum of time delay feeding the sheets to the next processing apparatus.

The function of the contact 86' of the relay 86 is to reduce the possibility of cobbling which might occur if only the contact 86'' were actuated by relay 86. If only a single contact 86'' were employed and, with the arm 16 in retracted position and the reverse limit switch 65 held closed, the sheet should inadvertently and accidentally be jarred or moved out of circuit completing contact with the contactor rings, the relay 86 would immediately be de-energized and its contact 86' would reclose. This would complete the circuit to the solenoid M which would be energized moving the valve V and starting the arm 16 to advance. However as soon as this advance started reverse limit switch 65 would be opened thus breaking the circuit to the solenoid M and causing the arm 16 to be returned to full retracted position and the reverse limit switch to again be closed. This cycle would repeat and oscillating or cobbling action would occur as long as the sheet did not complete the circuit to the relay 86. By providing the contact 86' as illustrated, if all contact between the sheets and the contactor rings is momentarily broken with the pickup arms in full retracted position and reverse limit switch 65 closed, both the contacts 86' and 86'' would immediately close because of de-energizing relay 86. When this occurs solenoid M will be energized as will also relay 85 which will close and become sealed in by closing of the contact 85'. Now the solenoid M will remain energized even after the arm 16 starts to advance and reverse limit switch 65 opens. However, as soon as the sheet resumes contact with the contactor rings the solenoid M will be de-energized and the pickup arms again retracted. Thus with the dual contacts 86' and 86'' there will be only one movement of the contact arms out of full retracted position and back to retracted position during any one given time that the sheets are momentarily out of engagement with the contactor ring, and rapid vibration or cobbling is prevented.

From the above description of the arrangement and mode of operation of my improved sheet handling apparatus it will be apparent that sheets or sets of sheets will be fed successively one after another with a minimum space therebetween regardless of the length of the sheets being fed. Furthermore the machine will continue to operate as long as there are sheets in the stacks to be picked up and moved. When it is desired to stop the operation it is only necessary to operate the stop push button 82 which breaks the circuit to relay 79 which in turn causes the contacts 79' and 79'' to open. The open-

ing of contact 79' unlocks relay 79 and opening of contact 79'' de-energizes relay 85 and solenoid M. De-energizing the solenoid causes the pickup arms to be retracted while de-energizing the relay 85 also opens the contact 85'. Thus the apparatus is rendered inoperative and will not start again until the start button 81 is closed.

Although I have described the illustrated embodiment of my invention in considerable detail it will be understood that modifications and variations may be made in the form and arrangement of the various elements which make up my improved sheet feeding apparatus. I do not therefore wish to be limited to the exact arrangement herein shown and described but claim as my invention all embodiments thereof coming within the scope of the appended claims.

I claim:

1. Apparatus for feeding electrically conductive sheets of magnetic material including, a stack support for holding a stack of sheets in generally vertical position, a magnetic roll adjacent said stack support, a pickup arm having a suction head supported at one end thereof, said pickup arm being mounted for movement in advancing and retracting directions between a position in which said suction head is more remote from said stack support than said roll and a position in which said suction head is closer to said stack support than said roll and is adapted to engage a sheet on said stack support, means for creating suction at said pickup head during a portion of the movement of said arm in retracting direction whereby a sheet will be picked up by said pickup head and removed from said stack, valve means operable by movement of said pickup arm for relieving the suction at said suction head substantially when a sheet carried thereby engages said magnetic roll during movement in retracting direction and before said arm reaches the end of said movement in retracting direction, means for imparting movement to said pickup arm in said advancing and retracting direction, and control means for said pickup arm advancing and retracting means whereby said arm, after being fully retracted, will start movement in advancing direction immediately upon, but not until, contact between the sheet being fed and said magnetic roll is broken.

2. Apparatus for feeding electrically conductive sheets of magnetic material including, a stack support for holding a stack of sheets in generally vertical position, a pair of vertically spaced magnetic rolls adjacent said stack support, a pickup arm having a suction head supported at one end thereof, said suction head having a resilient lip portion, said pickup arm being mounted whereby advancing and retracting movement of said arm will effect movement of said suction head between said rolls toward and away from said stack of sheets, means for creating suction at said pickup head during retracting movement of said arm whereby a sheet will be picked up from said stack, automatic means for cutting off the suction at said suction head during said retracting movement when said resilient lip portion thereof is substantially in a plane tangent to both of said magnetic rolls and before said arm reaches the end of said retracting movement, means for advancing and retracting said pickup arm, and control means for said arm advancing and retracting means whereby said arm, after being fully retracted, will start movement in advancing direction immediately upon, but not until, contact between the sheet being fed and the upper one of said magnetic rolls is broken.

3. Apparatus for feeding electrically conductive sheets of magnetic material including, a stack support for holding a stack of sheets in generally vertical position, a pair of vertically spaced rolls adjacent said stack support, magnetic means associated with upper one of said rolls for holding a sheet in engagement therewith, a pickup arm having a suction head supported at one end thereof, said suction head having a resilient lip portion, said pickup arm being mounted whereby advancing and retracting movement of said arm will effect movement of said

suction head between said rolls toward and away from said stack of sheets, means for creating suction at said pickup head during retracting movement of said arm whereby a sheet will be picked up from said stack, automatic means for cutting off the suction at said suction head during said retracting movement when said resilient lip portion thereof is substantially in a plane tangent to both of said rolls and before the end of said retracting movement, means for advancing and retracting said pickup arm, and control means for said arm advancing and retracting means whereby said arm, after being fully retracted, will start movement in advancing direction immediately upon, but not until, contact between the sheet being fed and said upper magnetic roll is broken.

4. Apparatus for feeding electrically conductive sheets of magnetic material including, a stack support for holding a stack of sheets in generally vertical position, a pair of vertically spaced magnetic rolls adjacent said stack support, a pickup arm having a suction head supported at one end thereof, said suction head having a resilient lip portion, said pickup arm being mounted whereby advancing and retracting movement of said arm will effect movement of said suction head between said rolls toward and away from said stack of sheets, a cylinder, a piston in said cylinder, operating connections between said piston and said pickup arm, fluid pressure conducting connections between said cylinder and said suction head, said piston being adapted to move in said cylinder during retracting movement of said arm to produce a reduced pressure in said fluid pressure conducting connections and suction head whereby a sheet will be picked up from said stack, automatic means for cutting off the suction at said suction head during said retracting movement when said resilient lip portion thereof is substantially in a plane tangent to both of said magnetic rolls and before the end of said retracting movement, means for advancing and retracting said pickup arm, and control means for said arm advancing and retracting means whereby said arm, after being fully retracted, will start movement in advancing direction immediately upon, but not until, contact between the sheet being fed and the upper one of said magnetic rolls is broken.

5. Apparatus for feeding electrically conductive sheets of magnetic material including, a stack support for holding a stack of sheets in generally vertical position, a pair of vertically spaced magnetic rolls adjacent said stack support, a pickup arm having a suction head supported at one end thereof, said suction head having a resilient lip portion, said pickup arm being pivotally mounted whereby advancing and retracting movement of said arm will effect movement of said suction head between said rolls toward and away from said stack of sheets, a cylinder, a piston in said cylinder, operating connections between said piston and said pickup arm, fluid pressure conducting connections between said cylinder and said suction head, said piston being adapted to move in said cylinder during retracting movement of said arm to produce a reduced pressure in said fluid pressure conducting connections and suction head whereby a sheet will be picked up from said stack, a normally closed atmospheric vent valve in said fluid pressure conducting connections, an operating arm supported for movement with said pickup arm, means on said operating arm disposed to engage and open said valve when said resilient lip portion of said suction head is substantially in a plane tangent to both of said magnetic rolls during retracting movement of said arm and before the end of such movement, means for advancing and retracting said pickup arm, and control means for said arm advancing and retracting means whereby said arm, after being fully retracted, will be maintained fully retracted until contact between the sheet being fed and the upper one of said magnetic rolls is broken.

6. Apparatus for feeding electrically conductive sheets of magnetic material including, means for supporting a

stack of sheets in generally vertical position, a pair of vertically spaced rolls adjacent said stack support, magnetic means associated with the upper one of said rolls for holding a sheet in engagement therewith, a pickup

5. arm having a suction head supported at one end thereof, said suction head having a resilient lip portion, said pickup arm being pivotally mounted whereby advancing and retracting movement of said arm will effect movement of said suction head between said rolls toward and away from said stack of sheets, a cylinder, a piston in said cylinder, operating connections between said piston and said pickup arm, fluid pressure conducting connections between said cylinder and said suction head, said piston being adapted to move in said cylinder during retracting movement of said arm to produce a reduced pressure in said fluid pressure conducting connections and suction head whereby a sheet will be picked up from said stack, automatic means for cutting off the suction at said suction head during said retracting movement when said resilient lip portion thereof is substantially in a plane tangent to both of said rolls and before the end of said retracting movement, means for advancing and retracting said pickup arm, and control means for said arm advancing and retracting means whereby said arm, after being fully retracted, will be maintained fully retracted until contact between the sheet being fed and said upper magnetic roll is broken.
10. 6. In combination in apparatus for feeding electrically conductive sheets of magnetic material, a stack support for holding a stack of sheets, a magnetic roll adjacent said support, means for driving said roll to feed a sheet in engagement therewith, a pickup arm having a suction head at one end and supported for advancing and retracting movement relative to said sheet support, power means for effecting said advancing and retracting movement, a solenoid, reversing means for changing said power means from advancing to retracting movement and vice-versa, operating connections from said solenoid to said reversing means, an operating circuit including electrical connections from a source of energizing current to said solenoid, a normally open reverse limit switch in said operating circuit, means for closing said reverse limit switch when said pickup arm is in full retracted position, a normally closed contact in said circuit in series with said solenoid and said reverse limit switch, and means for holding said normally closed contact open when a sheet is in engagement with said magnetic roll whereby said solenoid may be energized to initiate advancing movement of said pickup arm only when no sheet engages said magnetic roll and said pickup arm is in full retracted position.
15. 7. In combination in apparatus for feeding electrically conductive sheets of magnetic material, a stack support for holding a stack of sheets, a magnetic roll adjacent said support, means for driving said roll to feed a sheet in engagement therewith, a pickup arm having a suction head at one end and supported for advancing and retracting movement relative to said sheet support, power means for effecting said advancing and retracting movement, a solenoid, reversing means for changing said power means from advancing to retracting movement and vice-versa, operating connections from said solenoid to said reversing means, an operating circuit for said solenoid including electrical connections from a source of energizing current to said solenoid, a normally closed forward limit switch in said operating circuit disposed to be moved into and held in open position only while said pickup arm is in full advanced position, a normally open reverse limit switch in said operating circuit disposed to be moved into and held in closed position only when said pickup arm is in full retracted position, a control circuit for said solenoid including electrical connections to a source of control current, normally open contact means in said control circuit and supported adjacent said magnetic roll, said contact means being dis-

posed to be engaged and closed by a sheet only while said sheet is being fed by said roll, and a relay in said control circuit adapted to be energized when said normally open contact means is closed by a sheet and de-energized when said contact means is open, said relay having a normally closed contact in series with said reverse limit switch whereby said solenoid may be energized only when said reverse limit switch is closed and said second relay is de-energized.

9. In combination in apparatus for feeding electrically conductive sheets of magnetic material, a stack support for holding a stack of sheets, a magnetic roll adjacent said support, means for driving said roll to feed a sheet in engagement therewith, a pickup arm having a suction head at one end and supported for advancing and retracting movement relative to said sheet support, power means for effecting said advancing and retracting movement, a solenoid, reversing means for changing said power means from advancing to retracting movement and vice-versa, operating connections from said solenoid to said reversing means, an operating circuit for said solenoid including electrical connections from a source of energizing current to said solenoid, a normally closed forward limit switch in said operating circuit disposed to be moved into and held in open position only while said pickup arm is in full advanced position, a normally open reverse limit switch in said operating circuit disposed to be moved into and held in closed position only when said pickup arm is in full retracted position, a control circuit for said solenoid including electrical connections to a source of control current, normally open contact means in said control circuit and supported adjacent said mag-

netic roll, said contact means being disposed to be engaged and closed by a sheet only while said sheet is being fed by said roll, a first relay in said control circuit adapted to be energized when said normally open contact means is closed by a sheet and de-energized when said contact means is open, said first relay having a contact in series with said reverse limit switch, said relay contact being closed when said first relay is de-energized and open when said first relay is energized whereby said 5 solenoid may be energized only when said reverse limit switch is closed and said second relay is de-energized, and a second relay in said operating circuit, said second relay having a contact in said operating circuit in parallel with said reverse limit switch, said second relay contact being open when said second relay is de-energized and closed when said second relay is energized whereby, when both said normally open contact means in said control circuit is closed and said reverse limit switch is closed, said second relay will be locked in and said solenoid 10 will remain energized until said normally closed forward limit switch is opened upon said pickup arm reaching full advanced position.
